UNITED STATES PATENT OFFICE.

GUSTAVUS S. GRANLUND, OF WEST HAVEN, CONNECTICUT.

COMBINATION OF THE REVERSIBLE STEAM-TURBINE WITH LOCOMOTIVES AND VEHICLES.

SPECIFICATION forming part of Letters Patent No. 768,010, dated August 16, 1904.

Application filed October 30, 1903. Serial No. 179,180. (No model.)

To all whom it may concern:

Be it known that I, GUSTAVUS S. GRANLUND, a citizen of the United States, residing at West Haven, in the county of New Haven and State 5 of Connecticut, have invented a new and useful Combination of the Reversible Steam or Elastic-Fluid Turbine with Locomotives and Vehicles, of which the following is a specification.

- 10 My invention relates to improvements in locomotives and vehicles in which a reversible turbine furnishes the propelling power instead of the reciprocating engines now in use; and the objects of my invention are, first, to provide 15 a continuously-rotating turbine-shaft geared to the driving-axle of the locomotive, thereby lessening centrifugal effects of the reciprocating engine; secondly, to obtain a greater degree of expansion of steam or gas 20 by means of the compound reversible turbine. I attain these objects by the mechanism illustrated in the accompanying drawings, in which—

Figure 1 is a vertical section of part of the 25 combination; Fig. 2, a vertical section taken on line 1 2, Fig. 1; Fig. 3, a top view of the turbine with the upper half of the shell or cover removed; Fig. 4, a side view of the turbine with a section taken on line 9 10, Fig. 30 5; Fig. 5, a top view of the turbine with a section taken on line 11 12, Fig. 8. Fig. 6 is a vertical section of turbine, taken on line 7 8, Fig. 5; Fig. 7, a vertical section of turbine, taken on line 3 4, Fig. 5; Fig. 8, a vertical 35 section of turbine, taken on line 5 6, Fig. 5.

Similar letters refer to similar parts throughout the views.

The turbine-shaft P, to which are secured the vanes or fans I, Z, O, and U, is geared to 40 the locomotive driving-axle N by the gears X and Y, Fig. 3. The steam-pipe B, Fig. 1, communicating between the steam dome A of the steam-generator M and the turbine by the steam-passages r and s, carries the valve-seats z z, in which the piston-valves h and k are reciprocated by the rod l, attached to the lever G.

The turbine-shell is made in halves, T and R, bolted together, and the gear-cases W and 45 V are bolted to the turbine-shell, the turbine

being supported on the locomotive driving-axle by the bearing Q, attached to the shells T and R by the webs w and v.

The reversing-shaft L, supported by the bearings M^a and M^b, Fig. 5, carries the levers 55 d, b, and m, operating, respectively, the reversing-valves B^a, Fig. 6, B^b, Fig. 8, and B^c, Fig. 7, the shaft L being oscillated by the connecting-rod A, attached to the reversing-lever F, and connected to the crank C on 60 shaft L, Fig. 5.

The exhaust-pipe E carries the exhaust-steam from the turbine to the smoke-stack of the steam-generator M.

When the locomotive is moving forward, 65 the valves are reciprocated, so that valve K uncovers steam-passage S, causing the steam from dome A of steam-generator M to flow through passage D, Figs. 1 and 4, and impinge on vanes or fans I, Figs. 3 and 4, causing 70 the shaft P to rotate in a right-handed direction. The steam then escapes through passage B^m, Fig. 4, and shaft L having been oscillated passage C^c, Fig. 6, will be open and the steam impinge on vanes Z, whereupon it 75 passes through passage C^a into passage F^b, Fig. 8, impinging on vanes O, whence it passes through passage E^a and into passage D^c, Fig. 7, impinging on vanes U, after which it passes through exhaust-pipe E into the 80 smoke-stack.

When the locomotive is moving backward, the valve h is reciprocated until it uncovers passage r, Fig. 1, allowing steam from dome A of steam-generator M to pass through passage C, Figs. 1 and 4, and impinge on vanes I, after which it escapes through passage B^m and flows through passage C^b, Fig. 6, impinging on vanes Z. Passing through passage C^a the steam flows through passage F^a, 90 Fig. 8, expanding on vanes O, whereupon it passes through passage E^a and into passage D^a, expanding upon vanes U, Fig. 7, after which it exhausts into pipe E.

The front end of the turbine is supported 95 by the bracket x, Figs. 1, 4, and 5, resting on spring i, Fig. 1, which is held by the plate g upon the nut n of the bolt y, which is suspended from the angle-iron u, Figs. 1 and 2, resting upon the locomotive side frame f. 100

It is to be understood that the forms, dimensions, details, and materials employed in the construction of the combination may be varied without in any way changing the principle of the invention and that the words "locomotive" and "vehicle" are intended to include traction-engines, railroad cars and coaches, and automobiles.

Although the steam-turbine has been shown and described, any elastic fluid other than steam may be used, such as compressed air, or an explosive mixture of air and gas made from gasolene, kerosene, or coal.

As the steam or elastic-fluid turbine has been used in combination with torpedo-boats, cruisers, yachts, and merchant vessels, I do not claim such combination broadly.

The turbine-shaft running faster than the driving-axle transmits power through the reduction-gears.

Having described my invention, what I claim, and desire to secure by Letters Patent, is—

1. The combination with a locomotive or vehicle provided with a suitable running-gear including driving-axle and propelling wheel or wheels, of a reversible steam or elastic-fluid turbine comprising one or more series of vanes upon which steam or elastic fluid expands, a reversing mechanism admitting steam or elastic fluid on either side of turbine disks or vanes, a turbine-shaft connected with and arranged to run faster than the propelling-wheel or its axle, a suitable fuel-receptacle, a generator for steam or elastic fluid and a vehicle-body adapted to the conveyance of passengers and goods, a controlling mechanism for admitting or shutting off steam or elastic fluid, substantially as set forth.
2. The combination with a locomotive or ve-

hicle provided with a suitable running-gear including driving-axle and propelling wheel or wheels, of a reversible steam or elastic-fluid turbine comprising one or more series of vanes upon which steam or elastic fluid expands, a reversing mechanism admitting steam or elastic fluid on either side of turbine disks or vanes, a turbine-shaft connected with and arranged to run faster than the propelling-wheel or its axle, a suitable fuel-receptacle, a generator for steam or elastic fluid, and a suitable connection between the turbine and locomotive or vehicle running-gear, a controlling mechanism for admitting or shutting off steam or elastic fluid, substantially as set forth.

3. The combination with a locomotive or vehicle provided with a suitable running-gear including driving-axle or propelling wheel or wheels, of a reversible steam or elastic-fluid turbine comprising one or more compartments in which steam or elastic fluid expands, a reversing mechanism admitting steam or elastic fluid on either side of turbine disks or vanes, a turbine-shaft connected with and arranged to run faster than the propelling-wheel or its axle, a suitable fuel-receptacle, a generator for steam or elastic fluid, and suitable devices for transmitting motion from the turbine-shaft to the driving-axle or propelling-wheel, a controlling mechanism for admitting or shutting off steam or elastic fluid, substantially as set forth.

The foregoing specification of my improved combination signed by me, in the presence of two subscribing witnesses, on this 28th day of October, 1903.

GUSTAVUS S. GRANLUND.
